UNITED STATES PATENT OFFICE.

RALPH LEETE FOSTER, OF PROVIDENCE, RHODE ISLAND, ASSIGNOR TO KNIGHT & KNIGHT, INC., OF PROVIDENCE, RHODE ISLAND, A CORPORATION OF RHODE ISLAND.

DESIGN FOR AN IMAGE.

49,141.

Specification for Design.

Patented June 6, 1916.

Application filed March 31, 1916. Serial No. 88,176. Term of patent 3½ years.

To all whom it may concern:

Be it known that I, RALPH L. FOSTER, a citizen of the United States, residing at the city and county of Providence, State of Rhode Island, have invented a new and original and ornamental Design for an Image, of which the following is a specification, reference being had to the accompanying drawing, forming part thereof.

The figure is a perspective view of an image, illustrating my new design.

I claim:

The ornamental design for an image as shown.

RALPH LEETE FOSTER.

Witnesses:

HOWARD E. BARLOW,
A. F. MACREADY.
